ABSTRACT: A transistorized circuit for providing switching action includes main switching transistors and prestige transistors. The circuit also includes a multiwinding current transformer, the primary windings of which are connected in the main switching circuit so that the secondary outputs of the current transformer may be used to obtain driving sources for the prestige transistors. In a preferred embodiment, driving currents sufficient to cause the main switching transistors to full-saturate are always supplied to the prestige transistors by back-to-back diode circuits.

TRANSISTORIZED SWITCHING CIRCUIT

BACKGROUND OF THE INVENTION

This invention relates to a transistorized switching circuit and more particularly to a transistorized switching circuit having switching transistors and prestige transistors connected thereto wherein the switching transistors provide switching action by the application of control signals to the bases of the prestige transistors.

Generally speaking, where transistors are utilized as switching elements, it is possible to switch a large current on and off by means of a very small control signal, for example by using the Darlington connection, provided additional transistors are provided in a stage preceding the main switching transistors. However, transistors connected in the above manner require a large amount of power and it is impossible to operate them efficiently, so that in the prior art, it has been necessary to provide driving sources for exclusive use by the prestige transistors so as to eliminate said disadvantage.

However, the prestige transistors of such prior art circuits are driven by driving sources whose output does not change in response to changes in the main circuit current; the disadvantage of this being a greater power loss during normal operation when the main circuit current varies greatly or when the circuit is utilized as a switching element for an inverter to drive an electric motor.

Therefore, it is an object of the present invention to provide a transistor circuit for providing switching action which obviates the foregoing disadvantages of the prior art.

It is another object of the present invention to provide a transistor circuit characterized by reduced power consumption, high efficiency and reliable switching action.

It is a further object of the present invention to provide a transistor circuit in which the power loss is low even though it is subjected to an overload or heavy load.

SUMMARY OF THE INVENTION

The basic feature of this invention resides in a transistorized switching circuit which provides switching action characterized in that the primary windings of a current transformer are connected in the main switching circuit, the secondary outputs the current transformer being utilized to provide driving sources for the prestige transistors. The preferred embodiment resides in a transistor circuit based on the above circuit which is characterized in that driving currents sufficient to cause the main circuit transistors to full-saturate are always supplied to the prestige transistors by back-to-back diode circuits.

BRIEF DESCRIPTION OF THE DRAWINGS

FIG. 1 is a schematic diagram of an embodiment of a transistor circuit according to the present invention;

FIG. 2 is a schematic diagram of another embodiment according to the present invention;

FIG. 3 is a diagram showing a current characteristic in the embodiment of FIG. 1;

FIG. 4 is a schematic diagram of a further embodiment according to the present invention; and

FIG. 5 is a timing diagram relating to the further embodiment shown in FIG. 4.

DESCRIPTION OF THE PREFERRED EMBODIMENTS

FIG. 1 shows a DC power source E_d , a power transformer T , a current transformer CT having two primary windings and two secondary windings, and a pair of switching transistors Tr_{10} and Tr_{20} . The collector of the transistor Tr_{10} is connected through a primary winding n_{11} of the current transformer CT to one terminal P_1 of the transformer T . The emitter of transistor Tr_{10} is connected through the DC power source E_d to the center top O of the transformer T . The collector of the transistor Tr_{20} is connected through a primary winding n_{21} of

the current transformer CT to the other terminal P_2 of the transformer T . The emitter of transistor Tr_{20} is connected through the DC power source E_d to terminal O of the transformer T .

5 In this drawing there are also shown transistors Tr_{11} and Tr_{21} . The collector transistor Tr_{11} is connected through a secondary winding n_{12} of the current transformer CT to the emitter of the transistor Tr_{10} . The collector of the transistor Tr_{21} is connected through a secondary winding n_{22} of the current transformer CT to the emitter of the transistor Tr_{20} . L designates a load for example an electric motor or the like, and is connected to the secondary of the power transformer T . In addition, the conventional dot notation is used to represent the polarity of each winding of the transformer T and the current transformer CT.

10 In the foregoing circuit configuration, if the transistors Tr_{10} and Tr_{20} are energized in such a manner as to provide switching action, for example by causing them to conduct for a certain time interval, alternately by applying an input, alternately, to the bases of prestige transistors Tr_{11} and Tr_{21} , at terminals g_1 and g_2 , which, provide an amplifying action, an alternating voltage will be induced in the secondary of the transformer T .

15 For example, if the transistor Tr_{10} becomes conductive, a current i_c , corresponding to a load current i_L (see FIG. 5), flows in the primary winding n_{11} of the current transformer CT and through the transistor Tr_{10} , while in the secondary winding n_{12} of the current transformer CT, a current i_b is induced in a direction to counterbalance the effect of the ampere turns in the primary winding of the current transformer; this induced current i_b flows through the collector-emitter path of transistor Tr_{11} and the base-emitter path of the main transistor Tr_{10} . If the turns ratio of the primary and secondary windings 20 of the current transformer CT is taken to be K_1 , the foregoing induced current i_b becomes K_1 times the main circuit current i_c , (that is $i_b = K_1 i_c$) in magnitude. Therefore, if this turns ratio K_1 is made larger than the value of $1/\beta_1$, where β_1 the current amplification factor of the main circuit transistor Tr_{10} , the following relationship is valid:

$$i_c < \beta_1 i_b \quad (1)$$

Thus, the main transistor Tr_{10} can assume the fully saturated conductive state required for proper switching action. Similarly, if the value of the turns ratio K_2 for the primary and secondary windings n_{21} and n_{22} of the current transformer CT is selected so as to be larger than $1/\beta_2$, where β_2 is the current amplification factor of the main transistor Tr_{20} , when an input is supplied to the base of transistor Tr_{21} , the main transistor Tr_{20} instantly assumes the fully saturated conductive state. 25 Therefore, according to the present invention, the transistors will provide switching action with high efficiency and with little power loss. In addition, since the induced current of the current transformer which induced current serves as a driving source for transistors Tr_{11} and Tr_{12} increases and decreases in response to an increase and decrease in the main circuit current, in the present invention, it is, in contrast to the prior art, unnecessary to construct the circuit so that a current always flows which corresponds to the maximum load current. Thus, 30 it is possible to reduce power loss substantially in comparison to prior art circuits.

35 However, in the circuit shown in FIG. 1, since the driving current i_b for transistors Tr_{11} and Tr_{12} is not present unless the main current i_c flows, it is necessary to apply a differentiated input, in synchronism with the input to the bases of transistors Tr_{11} and Tr_{12} to the base of the main transistors Tr_{10} and Tr_{20} at the beginning of the conducting cycle of each transistor. Thus, 40 additional complex circuitry must be provided and various other problems result.

45 Another embodiment, shown in FIG. 2, overcomes the foregoing disadvantage, and differs from the embodiment shown in FIG. 1 in that a pair of diodes D_{10} and D_{11} are connected, respectively, between the collector of the transistor Tr_{11} and the collector of transistor Tr_{10} and between the collector of the transistor Tr_{11} and the secondary winding n_{12} of

the current transformer CT, with polarities as shown. Diodes D₂₀ and D₂₁ are similarly connected, between the collector of the transistor Tr₂₁ and the collector of transistor Tr₂₀ and between the collector of transistor Tr₂₁ and the secondary winding n₂₂ of the current transformer CT, with polarities as shown.

With this construction, if the normal input signal is applied to the base of transistor Tr₁₁, with the main current i_c absent, a current will flow from the collector of the main transistor Tr₁₀, through the diode D₁₀ and transistor Tr₁₁, to the base of the transistor Tr₁₁, causing transistor Tr₁₀ to become conductive. After transistor Tr₁₀ becomes conductive, the driving current i_b corresponding to the main current, is supplied through the secondary winding n₁₂ of the current transformer CT to transistor Tr₁₁ and, the same time, the diode D₁₀ will be reverse biased, so that the current i_b will be dissipated.

Further, in order to drive the main transistor Tr₁₀ into the fully saturated conductive state, even when the main current i_c is very large, it is necessary, as shown in FIG. 3, to provide a base current i_b', larger than the induced current i_b in the secondary of the current transformer CT. However, in this embodiment diode D₁₀ is present, so that when the collector-emitter voltage V_{CE} of transistor Tr₁₀ begins to increase, in response to the main current i_c becoming larger than the current value i_{c0} shown in FIG. 3, the voltage developed across the diode D₁₀ takes a direction to reverse the bias the same; thus, the base current needed to cause transistor Tr₁₀ to become full-saturated is supplied through the diode D₁₀ and transistor Tr₁₁. The result of this is that an excessive rise in the voltage V_{CE} between the collector and the emitter of transistor Tr₁₀ can be suppressed, so that when the circuit is subjected to transitional overload or heavy loads of short duration, the power loss in the transistors is much less than in prior art circuits, or in the embodiment shown in FIG. 1.

FIG. 4 shows a further embodiment of the present invention, comprising switching transistors Tr₃₀, Tr₄₀ and Tr₅₀, amplifying transistors Tr₃₁, Tr₄₁ and Tr₅₁, connected in front of the switching transistors Tr₃₀, Tr₄₀ and Tr₅₀, a transformer T, a current transformer CT, a load L, a DC power source Ed, and diodes D₁, D₂, ..., D₇₁, D₇₁'.

The collectors of transistors Tr₃₀ and Tr₄₀ are connected, respectively, through primary windings N₁₁ and n₁₁ of the current transformer CT to terminals P₁ and P₂ of the transformer T, and the emitters of transistors Tr₃₀ and Tr₄₀ are connected to a common junction point a. The collector of the transistor Tr₄₀ is connected to the junction point a and its emitter is connected, through the DC power source Ed, to the center tap terminal O of the primary winding of transformer T.

The diodes D₁ and D₂ are connected between the emitter of the transistor Tr₅₀ and the corresponding terminals P₁ and P₂ of the transformer T, with polarities as shown, and form a closed loop for the flow of a current of an opposite polarity to the load current through the transformer primary, in the event the load power-factor becomes leading or lagging, so that a time interval occurs during which the polarity of the load current is opposite to that of the output voltage. The diodes D₃ and D₄ are connected between terminal O of the transformer T and the common junction point a through, respectively, additional secondary windings N₁₁' and n₁₁' of the current transformer, with polarities as shown, to form a closed loop through transistors Tr₃₀ and Tr₄₀ for the flow of a current which corresponds to a lagging load current through the primary side of the transformer T, while a transistor Tr₅₀ is provided for controlling the conducting interval (which is controlled through a terminal g₃ during each half-cycle) is non-conductive, for example, in the event the load has a lagging power-factor. The diodes D₅₀ and D₅₁, D₆₀ and D₆₁, and D₇₀, D₇₁ and D₇₁' form back-to-back diode circuits, the operation of which was explained with reference to the embodiment of FIG. 2.

As explained above, the current transformer CT has primary windings N₁₁, n₁₁, N₁₁' and n₁₁'. The outputs derived through the secondary windings N₁₂ and N₁₃ of transformer

CT are utilized as driving sources for the transistors Tr₃₁ and Tr₅₁, and the other outputs which are derived through the secondary windings n₁₂ and n₁₃, are used as driving sources for the transistors Tr₄₁ and Tr₅₁. In this embodiment, the turns ratio of the respective windings are selected so that N₁₂=N₁₃, N₁₁'=N₁₁/2, n₁₂=n₁₃, and n₁₁'=n₁₁/2. Further, the conventional dot notation is used to represent the polarity of each winding of the transformer T and the current transformer CT.

In the foregoing arrangement, if the respective switching transistors Tr₃₀, Tr₄₀ and Tr₅₀ are rendered conductive in accordance with the timing diagram shown in FIG. 5, during time interval t1-t2 the following relationship is valid between the main current i_c and respective transistor driving currents i_{b3} and i_{b5}:

$$N_{11}i_c = N_{12}i_{b3} + N_{13}i_{b5} \quad (2)$$

and, if it is assumed that the load impedances of windings N₁₂ and N₁₃ are identical and that the numbers of turns in windings N₁₂ and N₁₃ are the same, the following relationship is valid:

$$i_{b3} = i_{b5} = (N_{11}/2N_{12})i_c = (N_{11}/2N_{13})i_c \quad (3)$$

Therefore, if the relationships between the winding ratios of N₁₁, N₁₂ and N₁₃, and the current amplification factors β_3 , β_5 of transistors Tr₃₀ and Tr₅₀ are selected in a manner similar to that explained with reference to FIG. 1, the following relationship can be obtained:

$$i_c < \beta_3 i_{b3} = \beta_5 i_{b5} \quad (4)$$

Thus, it is possible to turn transistors Tr₃₀ and Tr₅₀ into a fully saturated state.

Next, during time interval t2-t3, the transistor Tr₄₀ becomes nonconductive, so that in the event the load has, for example, a lagging power-factor, a current corresponding to a lagging load current i_L flows through the winding N₁₁ and the diode D₃. In this case, the magnetomotive forces established by the windings N₁₁ and N₁₁' counterbalance each other. However, the two windings have the mutual relationship N₁₁=2N₁₁', so the following equation is derived:

$$i_{b3} = (N_{11}/2N_{12})i_c < \beta_3 i_{b3} \quad (5)$$

Accordingly, the transistor Tr₃₀ becomes fully saturated. If winding N₁₁' is not connected, the value of the driving current i_{b3} becomes twice as large [i_{b3}=(N₁₁/N₁₂)i_c]; in this case the power loss increases and further, the switching speed of the transistor Tr₃₀ will be slowed down. In the above embodiment, one winding of the current transformer is connected in the commutating diode circuit, and thus prevents such a disadvantage from rising, by the use of the electromotive force generated by that winding.

Further, though there is a chance that a time interval (t0-t1), during which the polarity of the current may become reversed, may occur, depending upon the property of the load, as explained herein, at this time the main current i_c passing through the diode D₁ will not flow through any winding of the current transformer CT, so that during this period the driving current i_{b3} ceases, so no base current is lost.

Similarly, during the period t4-t5 the transistors Tr₄₀ and Tr₅₀ will be in the fully saturated state. Also, during the period t3-t4 the diode D₃ is reverse biased and the main current flows through the diode D₄; thus, the transistor Tr₄₀ turns into a fully saturated state.

In summary, the invention resides in a circuit in which prestige transistors are connected to the bases of the main circuit transistors and, by application of a very small control input to the bases of the prestige transistors, the main circuit transistors are caused to provide switching action, the invention being characterized by the fact that the prestige transistors are driven by the outputs of a current transformer connected in the main circuit; therefore, by establishing the foregoing relationship between the winding ratios of the current transformer and the current amplification factors of the main circuit transistors, it is possible to reduce power loss and to provide switching action at high efficiency. Further, since the base current of the main circuit transistors can be modified in response to the main circuit current, a minimally needed driving current always flows and thereby they are driven more efficiently.

While preferred embodiments of the invention have been described hereinabove, it is appreciated that variations and modifications may be made by one skilled in the art without departing from the spirit and scope of the invention.

What is claimed is:

1. In a switching circuit of the type which has at least two main switching transistors and in which prestige transistors are associated with the main transistors so that, by the application of control signals to the bases of said prestige transistors, said main circuit transistors provide switching action, the improvement which comprises a current transformer connected in the main circuit, the outputs of said current transformer

said at least two primary windings across the primary winding of said power transformer;
at least two prestige transistors, each connected in series with one of said secondary windings of the current transformer and with a diode between the common junction point of said two switching transistors and the base electrode of the corresponding switching transistor, said prestige transistors being driven alternately by an input applied to their base electrodes, and
two diodes, each connected between the junction between the primary winding of the power transformer and the corresponding switching transistor and the junction
